UNITED STATES PATENT OFFICE.

ANDY B. HARRELL, OF PILOT MOUNTAIN, NORTH CAROLINA.

TOBACCO-GRANULATOR.

SPECIFICATION forming part of Letters Patent No. 653,576, dated July 10, 1900.

Application filed July 20, 1897. Serial No. 645,274. (No model.)

To all whom it may concern:

Be it known that I, ANDY B. HARRELL, a citizen of the United States, and a resident of Pilot Mountain, in the county of Surry 5 and State of North Carolina, have invented certain new and useful Improvements in Tobacco-Granulators, of which the following is a specification.

This invention relates to tobacco-granulators; and it consists of the parts and combination of parts hereinafter set out.

In the drawings, Figure 1 is a vertical longitudinal section of a machine embodying my invention. Fig. 2 is a top plan of the 15 same.

A represents the base of the machine, on which are secured standards a, b, and c.

B is a screen-frame adapted to move between the standards of the machine. b' is a 20 delivery-spout connected to said screen-frame at one side and a short distance from the end of the frame.

b² is a bolting-cloth stretched across the bottom of the screen-frame from the front of 25 the frame to the near edge of the spout b'.

b³ is the screen, stretched entirely across the top of the screen-frame and immediately above the bolting-cloth. The rear end of the frame above the screen b³ is open at b⁴. The 30 rear end of the frame between the screen and bolting-cloth is closed and slants toward the edge of the delivery-spout, as at b⁶, which registers with a similar bevel on the lower edge of the casing of the machine, thereby forming a 35 guide for said screen.

C is a tapered hopper mounted on the top of the machine the small end of which leads into a hood c, which may be of any desired shape. Immediately below the hood is a concave portion c', provided with knife-edged 40 teeth. This concave portion c' is removable for purposes of cleaning and sharpening said teeth.

c² is a chute extending from the concaved

portion into the screen-frame. The concaved 45 portion c' is held in place by means of the rod c³, which passes through the standards a and through a groove in the top of said concaved portion.

D is a shredder or granulator consisting of 50 a cylinder having radial knife-edge teeth which intermesh with the teeth on the concave portion.

d is a shaft upon which the cylinder D is mounted. d' is a band-pulley mounted on 55 one end of said shaft.

As will be seen, one edge of the concaved portion rests flat on a cross-sill and has a groove in its upper edge, in which the rod C³, runs parallel therewith from side to side of 60 the frame of the machine, thus holding the said portion securely in place against movement incident to the shake or jar of the operating parts of the machine. The rod C³ is provided with threads (not shown) on its end, 65 whereby sides of the machine may be drawn up tight against the ends of the concave, whereby the concave is always in a central position with reference to the side of the machine, thereby insuring the intermeshing of 70 its teeth with those on the cylinder at all times, thus obviating damage to said teeth by reason of contact incident to loose and worn parts.

I claim—

In a tobacco-granulator, the combination 75 with the frame, the shredder journaled in the sides thereof and the toothed concave member, a locking-groove formed in its upper edge, of a locking-rod C³ having threads on 80 one end, said rod extending from side to side of the frame and seated in the groove on the concave member, substantially as and for the purpose specified.

ANDY B. HARRELL.
